UNITED STATES PATENT OFFICE.

THEODORE HAVILAND, OF AMBAZAC, FRANCE.

DESIGN FOR A COVERED DISH.

SPECIFICATION forming part of Design No. 24,994, dated December 24, 1895.

Application filed September 26, 1895. Serial No. 563,804. Term of patent 7 years.

To all whom it may concern:

Be it known that I, THEODORE HAVILAND, a citizen of the United States, residing at Am-bazac, in the Department of Haute-Vienne, 5 Republic of France, have invented and produced a new and original Design for Dishes; and I do hereby declare the following to be a full, clear, and exact description of the same, reference being had to the accompanying 10 drawings, forming a part thereof.

The principal feature of my design consists of a covered dish of irregular shape separated into compartments. The periphery of the cover and the base of the dish are marked by 15 scroll and shell like ornamentations. The handles are formed to resemble olive branches ornamented with olive berries, and are attached to the body of the dish with simulated 20 ribbons.

Figure 1 represents a side view of the dish; Fig. 2, a face view of the cover.

In Fig. 1, A represents the handles of the dish which simulate olive branches with berries as they were growing on the branches, the ends of the handles on the dish, as well as on 25 the cover, are attached by simulations of ribbons to the body of the dish and cover. The base of the dish and the periphery of the cover are irregular in shape and decorated with scroll and shell like ornamentation. The letters C C mark the compartments into which 30 the dish and cover are divided.

What I claim is—

A design for a dish substantially as shown and described. 35

In testimony whereof I have affixed my signature in presence of two witnesses.

THEODORE HAVILAND.
